UNITED STATES PATENT OFFICE

FRANK CONRAD, OF PENN TOWNSHIP, ALLEGHENY COUNTY, PENNSYLVANIA, AS
SIGNOR TO WESTINGHOUSE ELECTRIC & MANUFACTURING COMPANY, A CORPORA-
TION OF PENNSYLVANIA

CONSTANT-FREQUENCY GENERATOR

Original application filed January 18, 1929, Serial No. 333,874. Divided and this application filed March 5, 1930. Serial No. 433,483.

This application is a division of my application, Serial No. 333,874, filed January 18, 1929.

My invention relates to high frequency generators of the tuning-fork or vibrating-reed type.

The object of my invention is to provide means for maintaining the frequency of a generator of the above-mentioned type constant.

In practicing my invention, I employ a tuning fork which is mounted in a block of metal and driven by electromagnetic means. The frequency of vibration of the tuning fork is maintained constant by periodically heating the tuning fork by an amount that is dependent upon the departure of the vibrations from the desired frequency. The heat is applied periodically to the tuning fork by means of a heater element which is in contact with the metal block and is connected to a system including an electric clock and a synchronous motor, as will be more fully described hereinafter.

Other features and advantages of my invention will appear from the following description, taken in connection with the accompanying drawings, in which,

Figure 1 is a diagrammatic view of the apparatus and electrical connections employed in my constant-frequency generator;

Fig. 2 is a diagram to aid in describing the operation of my constant-frequency generator;

Fig. 3 is a diagrammatic view of the heating box and heating apparatus for the constant-frequency-generator tuning fork;

Fig. 4 is an end elevational view of the tuning fork and its holder and driving mechanism, and

Fig. 5 is a sectional view, taken along the line V—V of Fig. 4.

Referring to the drawings, the portion of a constant-frequency-generator system, indicated in Fig. 1 by the legend "heater and fork", is shown schematically in Fig. 3. This portion of the system comprises a heat-insulated box 67 within which are located two electric heaters 68 and 69. The upper heater 68 is connected to a source of current through

a thermostatic relay 70 of the bimetallic type. A condenser 71 is shunted across the relay contacts to reduce sparking. The interior of the heater box is maintained at a substantially constant temperature by means of the heater 68 and the thermostatic relay 70. The heater 69, which may be an ordinary flat-iron heater, is provided for applying heat directly to the tuning-fork holder 72, the amount of heat which is applied being controlled by means of the circuit shown in Fig. 1. The elements 73 and 74, connected to the conductors 75 and 76, respectively, are electromagnetic devices for driving the tuning fork.

The construction of the tuning-fork holder 72, the tuning fork, and the electromagnetic driving means 73 and 74 can best be understood by referring to Figs. 4 and 5. The holder 72 comprises two solid metallic blocks 77 and 78, preferably of brass, each having a vertical hole 79 drilled off center, therein. Each block has a larger threaded hole, drilled at right-angles to the vertical hole 79 and communicating with it, in which one of the electromagnetic driving units 73 and 74 is supported. The two blocks 77 and 78 are clamped together by means of bolts 80, with their thin walls adjacent to each other and with a sheet of magnetic material 81 between them. In this way, two well portions 79 are formed, separated by a thin partition of magnetic material 81 and non-magnetic material 82. A square notch 83 is cut in the middle of the upper edge of the partition. The tuning fork 84 is clamped, by means of bolts 85, between two solid metal blocks 86 and 87, preferably of brass. Blocks 86 and 87 are secured, by bolts 88, to the blocks 77 and 78 in such position that a portion of the tuning fork 84 is located within the notch 83 cut in the partition, while the prongs 99 are located within the wells 79. A clip 100 is attached at the top of the block for holding a thermometer 101.

The tuning-fork-driving elements 73 and 74 comprise telephone-receiver units having pole pieces adjacent to the prongs 99 of the tuning fork 84. The pole pieces are soft-iron pieces attached to the poles of a permanent magnet 102. They have coils 103

mounted thereon which are connected to the binding posts 104. The driving elements are held in place by means of set screws 105.

The partition above-specified is provided for electrically shielding the driving elements 73 and 74 from each other.

Since the tuning fork 84 is in contact with the brass blocks 86 and 87, which are good heat conductors, the temperature of the fork 84 may be controlled by varying the amount of heat applied to these blocks. This is done by setting the fork holder 72 upon an electric heater 69, as shown in Fig. 3, and by controlling the amount of current flowing through the heater by means of the circuit shown in Fig. 1.

Referring to Fig. 1, the constant-frequency current is generated by so connecting the fork-driving elements 73 and 74 to an amplifier 106 that the fork 84 is vibrated at its natural frequency. In the example being described, a 5000-cycle current is generated. The driving element 74 is connected to the input of the amplifier 106 by conductors 76, while the driving element 73 is connected to the output of the amplifier 106 by conductors 75. By means of this arrangement, the fork 84 is driven at its natural frequency by the energy supplied from the amplifier 106, and a current of this frequency can be obtained from the amplifier output.

The frequency of the current generated is controlled by varying the amount of heat supplied through the heater circuit 107 to the fork heater 69. The amount of heat supplied to the fork 84 is controlled by means of a synchronous motor 108 (preferably of the phonic-wheel type) connected to the fork-amplifier output through an amplifier 109, and by means of an electric clock 110.

When a current of the desired frequency is being generated, the synchronous motor 108 connects the fork-heater circuit 107 to a source of current at regular intervals, while the electric clock 110 disconnects the heater circuit 107 from the source at like intervals. In this way, the fork heater 69 is alternately connected to, and disconnected from, the source of current, which, in the example illustrated, is a 110-volt alternating-current supply.

The circuit connecting the current supply to the fork heater 69 may be traced from one terminal of the 110 volt source, through a conductor 111, a resistor 112, the armature 113 of a relay 114, a contact of relay 114, an ammeter 115, a second resistance 116, an indicator lamp 117 and resistance 118, in parallel, a conductor 119, one conductor of line 107, the fork heater 69, the other conductor of line 107 and the conductor 120, back to the other terminal of the alternating-current supply. The winding of relay 114, which pulls up the armature 113 and thereby connects the fork heater 69 to the alternating-

current supply, has one terminal connected to ground and the other terminal connected, through a resistance 121 and a conductor 122, to one terminal of a battery 123, the other terminal of the battery 123 being connected to ground.

A polar relay 124, having an armature 125 connected to ground, is provided for connecting the right-hand terminal of the winding of relay 114 to ground through the conductor 126 and relay contact. It is evident that, when the armature 125 of the polar relay 124 rests against the left-hand contact, the armature 113 of the relay 114 is pulled up to connect the fork heater 69 to the 110 volt supply. When the armature 125 of the polar relay 124 rests against the right-hand contact, the winding of the relay 114 is short circuited, and the armature 113 drops down, thus disconnecting the fork heater 69 from the 110 volt supply.

The armature 125 of the polar relay 124 is pulled over to the left, to connect the fork heater 69 to the 110 volt supply, each time the upper terminal of the left-hand winding 127 of said relay is connected to ground by means of the synchronous motor 108 through the conductor 128, brush 129, contact element 130, shaft 131, ring 132 and brush 133. The shaft 131 is connected to the synchronous motor 108 through a gear reduction unit so that contact between element 130 and brush 129 is made once every two seconds if the tuning fork 84 is vibrating at the proper frequency.

The polar relay armature 125 is pulled against the right-hand contact, to disconnect the fork heater 69 from the 110-volt supply, each time the electric clock 110 pulls the armature 134 of the polar relay 135 against the left-hand contact. Since the electric clock 110 actuates the polar relay 135 at regular intervals, (once every two seconds, in the example illustrated) the fork heater 69 will be disconnected from the 110-volt supply at like intervals. The synchronous motor 108 and the electric clock 110 are so adjusted with respect to each other that they alternately connect and disconnect the fork heater 69 and the current supply. The electric clock 110 is, preferably, of the type described and claimed in my copending application, Serial No. 176,061, filed March 17, 1927, in which the pendulum is driven by charging and discharging a condenser through a driving coil. The coil of the polar relay 135 is connected in series with this driving coil.

When the armature 134 is pulled against the left-hand contact, a circuit is completed from a battery 136, through a resistance 137, a conductor 138, a relay winding 139, a conductor 140, the relay armature 134 and the left-hand contact, back to the battery 136. This pulls the relay armature 141 against the upper contact and connects the upper terminal of the right-hand winding 142 of the polar relay 124 to ground through conductor

143 and armature 141. The armature 125 of the polar relay 124 is then pulled against the right-hand contact, and relay armature 113 drops, thereby disconnecting the heater 69 from the current supply.

5 A special circuit is provided for passing current through the polar-relay windings 127 and 142 in response to the closing of either the synchronous motor or the electric-clock contacts. The circuit comprises the battery 123 which is connected, through a conductor 144, a resistance 145 of a few hundred ohms and a second resistance 146 of several meg-ohms, to one terminal of a condenser 147. The other terminal of the condenser 147 is connected to the other terminal of the battery 123 through ground. A circuit is likewise completed from one terminal of the battery 123, through the conductor 144, the resistance 145, a second resistance 148 similar to resistance 146, a condenser 149 similar to condenser 147 and, through ground, to the other terminal of the battery 123.

10 By means of the circuit described above, the condensers 147 and 149 are kept charged. Accordingly, when the upper terminal of either polar-relay winding 127 or winding 142 is connected to ground, by means of the synchronous motor 108 or the electric clock 110, the condenser to which the winding is connected discharges through that winding. This momentary flow of current through the winding is sufficient to pull the armature 125 against a contact. Because of this arrangement, the armature 125 of the polar relay 124 may be pulled away from a contact very shortly after it is pulled against it, since the rush of currents lasts a very short time. Therefore, the armature 125 of the relay may be pulled away from a relay contact even though the contacts of the synchronous motor 108 or those of electric clock 110, which pull the armature 125 against the relay contact, are still closed.

15 The condensers 150 and resistances 151 are employed to reduce sparking at the relay contacts.

The following values of capacity, resistance and voltage have been found satisfactory although, obviously, other values may be employed, if desired: resistances 146 and 148 equal 5 megohms; resistance 145 equals 1000 ohms; resistance 112 equals 50 ohms; resistance 116 equals 800 ohms; resistance 118 equals 20 ohms; condensers 147 and 149 equal .25 micro-farads; resistance 121 equals 10,000 ohms; and the voltage of battery 123 equals 350 volts.

20 The operation of the circuit will be more fully understood by referring to the diagram of Fig. 2 which greatly exaggerates the rapidity with which changes in the fork frequency occur. In this diagram, the current applied to the fork heater 69 is plotted against time in seconds. From zero to four

25 seconds, the generator is supplying a current of the proper frequency, that is, 5000 cycles per second. Accordingly, the fork heater 69 is alternately connected to, and disconnected from, the current supply at one-second intervals. When the fork 84 begins to vibrate too slowly, the synchronous motor 108 slows down, and, after the heater 69 has been disconnected from the current supply (as after the four-second interval) it is not again connected to the current supply until a longer time than one second. The electric clock 110, however, is not affected by the frequency of the tuning fork 84 and continues to disconnect the current from the fork heater 69 at two second intervals. The current supply is accordingly disconnected from the heater 69 at the six-second interval. It will be noted from the diagram that, as a result, less heat is applied to the fork 84 than when it is vibrating at the proper frequency. Accordingly, the tuning fork 84 will be cooled slightly and its frequency will increase. In the diagram, the fork frequency begins to increase after the ten-second interval. After the twelve-second interval, the fork 84 begins to vibrate too rapidly, and the synchronous motor 108 speeds up. This results in heat being applied to the fork 84 an instant sooner than it would be if the fork were vibrating at the 5000-cycle frequency. The temperature of the fork 84 is, accordingly, increased and its frequency is changed the desired amount.

30 It will be noted that, at the sixteen-second interval, the fork 84 is vibrating so rapidly that the synchronous motor 108 connects the heater 69 to the current supply as soon as it is disconnected by the electric clock 110. It is evident that, if the fork 84 vibrates still more rapidly, the synchronous-motor speed will be so high that its contact 180 will connect the fork heater 69 to the current supply just before the contacts of relay 139 are closed by the electric clock 110 to disconnect the current supply from the heater. When this happens, less, instead of more, heat is applied to the fork 84 than is applied when it runs at the proper frequency, and the system will not correct the fork frequency. In such case, a manual adjustment must be made to increase the fork temperature. Under ordinary conditions, no such adjustment is necessary. In the 5000-cycle generator described, the synchronous motor 108 connects the fork heater 69 to the current supply every 10,000 cycles, while the electric clock 110 disconnects the fork heater 69 from the current supply every two seconds.

35 Various modifications may be made in my invention without departing from the spirit and scope thereof and I desire, therefore, that only such limitations shall be placed thereon as are imposed by the prior art and set forth in the appended claims.

I claim as my invention:

1. A constant-frequency generator comprising a mechanical element having a natural period of vibration, means for vibrating said element at its natural frequency, and means responsive to changes in the frequency of the output of said generator for maintaining the frequency of vibration of said element constant. 73
2. A constant-frequency generator comprising a mechanical element having a natural period of vibration, means for vibrating said element at its natural frequency, and means for applying heat to said element, said means being responsive to changes in the frequency of the output of said generator for changing the amount of heat applied to said element. 78
3. A constant-frequency generator comprising a mechanical element having a natural period of vibration, means for vibrating said element at its natural frequency, means for applying heat to said element at periodic intervals, and means responsive to the frequency of vibration of said element for controlling the time between said intervals. 83
4. A constant-frequency generator comprising a mechanical element having a natural period of vibration, means for vibrating said element at its natural frequency, and means responsive to the frequency of vibration of said element for applying heat thereto in increments having a magnitude dependent upon said frequency. 88
5. A constant-frequency generator comprising a mechanical element having a natural period of vibration, means for vibrating said element at its natural frequency, means for heating said element, a source of current, means responsive to the frequency of said element for connecting said source to said heating means and means for disconnecting said source from said heating means at regular intervals. 93
6. A constant-frequency generator comprising a mechanical element having a natural period of vibration, means for driving said element at its natural frequency, means including an electric heating element, for heating said mechanical element, a source of current, means for connecting said source to said heating element at intervals dependent upon the frequency of vibration of said element, and means for disconnecting said source from said heating element at regular intervals. 100
7. A constant-frequency generator comprising a mechanical element having a natural period of vibration, means for vibrating said element at its natural frequency, means, including an electric heating element, for heating said element, a source of current, means for alternately connecting and disconnecting said source and said heating element and means for making the time be- 105
- tween said connection and disconnection dependent upon the frequency of vibration of said element. 110
8. A constant-frequency generator comprising a mechanical element having a natural period of vibration, means for vibrating said element at its natural frequency, means, including an electric heating element, for heating said mechanical element, a source of current, means for connecting said source to said heating element after said mechanical element has vibrated a predetermined number of cycles and means for disconnecting said source from said heating element at intervals independent of the frequency of vibration of said mechanical element. 115
9. A constant-frequency generator comprising a mechanical element having a natural period of vibration, means, including an electric heating element, for heating said mechanical element, a source of current, means, including a synchronous motor driven by said generator, for connecting said source to said heating element and means, including an electric clock, for disconnecting said source from said heating element. 120
10. A constant-frequency generator comprising a mechanical element having a natural period of vibration, means for vibrating said element at its natural frequency, means responsive to the frequency of said element for heating it and means for making said heating means ineffective at fixed intervals. 125
11. A constant-frequency generator comprising a mechanical element having a natural period of vibration, means for vibrating said element at its natural frequency, means for heating said element, means for making said heating means ineffective at intervals spaced apart by a predetermined number of vibrations of said mechanical element and means for making said heating means ineffective at evenly spaced time intervals. 130
12. A constant-frequency generator comprising a mechanical element having a natural period of vibration, means for vibrating said element at its natural frequency, means for heating said element, means for making said heating means effective at intervals spaced apart by a period of time proportional to a predetermined number of vibrations of said element, and means for making said heating means ineffective the same number of times it is made effective and at regular intervals, independent of the frequency of said element. 135
13. A constant-frequency generator comprising a mechanical element having a natural period of vibration, means for vibrating said element at its natural frequency, means for heating said element, a polar relay, a plurality of condensers connected to said relay, means for charging said condens- 140

ers, means for operating said relay and making said heating means effective when one of said condensers is discharged and means for operating said relay and making said heating means ineffective when another of said condensers is discharged.

14. A constant-frequency generator comprising a mechanical element having a natural period of vibration, means for vibrating said element at its natural frequency, means for heating said element, a polar relay having an armature and two windings, each of said windings having a condenser connected thereto, means for charging said condensers, means for making said heating means effective when current is passed through one relay winding, means for making said heating means ineffective when current is passed through the second relay winding, means responsive to the frequency of vibration of said element for discharging one of said condensers through said one relay winding, and means independent of the frequency of said element for discharging the other condenser through the second relay winding at regular intervals.

15. A constant-frequency generator comprising a mechanical element having a natural period of vibration, means for vibrating said element at its natural frequency, heating means for heating said element, means for alternately making said heating means effective and ineffective, and means for making the time between the instant the heating means is made effective and the instant it is made ineffective dependent upon the frequency of vibration of said element.

In testimony whereof, I have hereunto subscribed my name this 26th day of February, 1930.

FRANK CONRAD.
